UNITED STATES PATENT OFFICE

CARL F. KAPPLER, OF PHILADELPHIA, PENNSYLVANIA, ASSIGNOR TO SIMON FRIED-
BERGER, OF PHILADELPHIA, PENNSYLVANIA

MACHINE FOR MAKING FABRIC

Application filed August 1, 1928. Serial No. 296,712.

This invention relates to a machine adapted for the manufacture of an open-work fabric, and particularly relates to a machine capable of producing fringe on a fabric having warp threads consisting of chain stitches interlocked with filler threads.

A satisfactory open-work fabric particularly adapted for the production of towels, wash-cloths and other similar goods has been found to be a fabric which is composed of chains of knitted loops connecting filler threads which are deflected cross-wise of said loops. A fabric of this sort which has been found very satisfactory in use is disclosed in the patent to Clewley, No. 1,139,343 of May 11, 1915. In the fabric disclosed in this patent, filler threads are criss-crossed and interlocked with the lines of chain stitches, open spaces being left between adjacent chains at certain portions which are devoid of crossing threads, thus increasing the porosity and openness of the fabric. Prior to the fabric disclosed in the Clewley patent referred to above, such fabric was made using a single thread for each line of chain stitches. The chains in such fabric would readily unravel. Such possibility of unravelling was avoided by the adoption of the mode of manufacture disclosed in the Clewley patent.

The machine of the present invention may be used to so modify either the fabric disclosed in the Clewley patent or that formed prior to the use of the fabric disclosed in the Clewley patent, imparting thereto not only an ornamental fringe but also, by forming a tightly bound fringe, eliminating to a very high degree the possibility of unravelling, which usually commences at the cut end of the fabric.

It is a primary object of the present invention, accordingly, to provide a machine which will operate to produce an open-work fabric of the type described having fringe portions between successive lengths thereof which may be cut with the provision of fringe on the individual articles formed, and which fringe will have the threads composing the same so tightly bound together that ravelling is prevented. A further object of the present invention consists in the

provision of a simple mechanism to accomplish the results sought for. These objects will become more apparent as the following description is read in connection with the accompanying drawings, in which:

Fig. 1 is an elevation of a portion of the rear of a knitting mechanism showing the control means for producing the results indicated above.

Fig. 2 is an end elevation of the mechanism shown in Fig. 1.

Fig. 3 is a horizontal sectional view on a plane directly above the horizontal arm of lever 16 showing the control mechanism of Figs. 1 and 2.

Fig. 4 is a pattern chain adapted to control the thread guides.

Fig. 5 is a second chain arranged to control the thread guides.

Fig. 6 is a diagrammatic plan view of a section of fabric produced by the machine.

Fig. 7 is a diagrammatic representation illustrating the interaction between the lines of chain stitches and the filler threads.

The machine of the present invention is of a common construction used in the art and the same is accordingly not shown in detail, reference being made to Aaron Patents Nos. 779,109 and 781,387, dated respectively, January 3, 1905, and January 31, 1905, which disclose details of construction. As illustrated in Fig. 1, the machine comprises a plurality of upstanding latch needles 2 carried by a reciprocating needle bar 4. Threads are fed to these needles and crossed between them in order to form filling by means of thread guides 6 carried by guide bars 8, which are mounted for oscillatory and longitudinal movement in the usual manner. Threads 10 are fed to the thread guides from a suitable beam or beams 12 mounted in the frame of the machine. Guide bars 8 have imparted thereto their longitudinal movements through links 14. In the present machine, to form the fabric disclosed only two guide bars are necessary, the front guide bars carrying the guides for the threads which form the chain stitches, while the rear guide bar carries the threads which form the filler. The link connected to the rear guide bar is secured

at its outer end to a bell crank lever 16. The front guide bar is similarly secured to a bell crank lever 18. These bell crank levers have horizontal arms provided with followers 20 which ride over the pattern chains. A drum 22, suitably mounted in the frame, is driven through a pair of gears 24 from a shaft 26, which forms part of the operating mechanism of the machine. A chain 28 which is driven 5 by means of teeth on drum 22, is provided with cam portions which engage the follower of bell crank lever 18 and thus impart suitable longitudinal movement to the guide bar operated thereby.

15 It will be noted that bell crank lever 18 is mounted in a fixed axial position on a shaft carried by the frame of the machine. Bell crank lever 16 is loosely mounted on the same shaft and is pressed in one direction by a 20 spring 30. When moved into the position into which it is urged by spring 30, the follower of lever 16 engages a chain 32 carried by the drum. A second chain 34 is carried by the drum at one side of chain 32. Pivoted 25 to the frame of the machine is a bell crank lever 36 which has a forked end 38 engaging in the hub of lever 16 to move the same axially against the pressure of spring 30, so that the follower carried by lever 16 may be 30 brought over chain 34. It will thus be observed that a rocking of lever 36 will cause a selective operation of bell crank 16 by either chain 32 or chain 34, so as to produce thereby a different cycle of movement of the rear 35 guide bar.

Rocking movement is imparted to bell crank 36 by means of a cam 40 provided with an outwardly extending nose 42 which, by engagement with the horizontal arm of the 40 bell crank, will cause lever 16 to be actuated by chain 34. Cam 40 is, through the medium of suitable gears, driven from a shaft which carries a ratchet wheel 44. A detent 46 prevents rotation of ratchet wheel 44 in one 45 direction while permitting its free movement in the other direction. A third chain 50, carried by drum 22, is provided with a link having an upstanding cam portion 48, which cam portion is adapted, during the movement 50 of chain 50, to engage with the teeth of ratchet wheel 44 and move the same through an arc corresponding to one tooth during each complete cycle of movement of chain 50.

A brake 52 is provided for beam 12 and 55 comprises a lever pivoted at 54 to the frame of the machine. A link 56, pivoted at its lower end to the horizontal arm of bell crank 36, extends upwardly through a bracket 58 in brake lever 52 and is provided at its top 60 with a thumb nut 60. Interposed between bracket 58 and thumb nut 60 is a spring 62. By adjustment of thumb nut 60, the tension of the spring may be so regulated as to regulate the tension on drum 12 and accordingly 65 the tension on threads 10. Upon oscillation

of bell crank lever 36 by nose 42, spring 62 will be compressed with resultant increase of tension on the threads.

In the operation of the machine, assuming nose 42 to be out of operative relationship with lever 36, the machine will operate in the usual fashion, bell crank 18 being acted upon by chain 28 to oscillate the front guides to produce a series of chain stitches, while bell crank 16 will be operated by chain 32 to feed the threads passing through the rear thread guides cross-wise of the chains, so as to interlock the filler threads therewith. Reference to Fig. 4 will show that chain 32, a portion of which is shown, consists of links having three different heights. The resultant action forms a fabric 64 in the manner diagrammatically illustrated in Fig. 7, in which lines 66 represent the lines of chain stitches and 68 represent the filler threads interlocked therewith. It will be noted that during a portion of a cycle, the filler threads are given a relatively slight oscillation, while at other times a large oscillation is imparted thereto, so that they are carried across a series of chains adjacent those with which they were previously interlocked. The result is the production of a fabric such as illustrated at the top and bottom of Fig. 6, having staggered openings therein. The appearance of this fabric is well shown in Clewley Patent No. 752,033, dated Feb. 16, 1904.

During the rotation of drum 22, it will be observed that chain 50 will be carried around therewith, and during each complete cycle of chain 50, cam portion 48 carried thereby will engage ratchet wheel 44, advancing the same a distance corresponding to one of the teeth thereof. Accordingly, during each cycle consisting of a number of cycles of movement of chain 50 corresponding to the number of teeth on ratchet wheel 44, nose 42 will be brought into engagement with lever 36, rocking the same in a clockwise direction, as viewed in Fig. 2. Upon the bringing of nose 42 into contact with lever 36, it will remain in such position until chain 50 passes through another cycle of movement. It will then be released therefrom by movement of ratchet wheel 44.

During the period when lever 36 is oscillated as described, lever 16 is brought over chain 34 which, as shown in Fig. 5, comprises alternate high and low portions which will produce a zig-zag motion of filler threads 68. At the same time, the tension on beam 12 is increased. As a result, fringe portion 70 will be produced, corresponding in length to the cycle consisting of a single revolution of chain 50.

Upon movement of nose 42 out of engagement with lever 36, lever 16 moves forwardly into engagement with chain 32 and the old cycles, forming the body of the fabric, are resumed. Another fringe section will then

not be produced until a complete revolution of nose 42 takes place, which, as stated above, only occurs after chain 50 has passed through a number of cycles corresponding to the number of teeth in ratchet wheel 44.

5 It will be obvious that by changing the number of links in the various chains and the height of the cam portions thereof, that the characteristics of the fabric may be readily changed. The interval between the successive fringe portions may obviously be changed by replacement of ratchet wheel 44 or of chain 50. The machine may also be used to manufacture various types of fabric, 10 so that the disclosure is not intended to limit this invention to a machine for making only the particular fabric disclosed.

15 Having now fully described my invention, what I claim and desire to protect by Letters Patent is:

20 In a fabric making machine including a plurality of needles and thread guides movable to present threads to said needles, a plurality of means for controlling the movements of the thread guides, means for selectively rendering the controlling means operative, spring pressed means for maintaining a definite and substantial minimum tension upon a group of threads passing to the 25 needles, and means for increasing the tension during operation under the control of one of the controlling means.

30 In testimony of which invention, I have hereunto set my hand, at Philadelphia, Pennsylvania, on this 16th day of July, 1928.

CARL F. KAPPLER.
